Primary Examiner — Brett Miller*Assistant Examiner* — Rani J Abdallah(74) *Attorney, Agent, or Firm* — Ruggiero McAllister & McMahon LLC**CLAIM**

We claim the ornamental design for the actuator button, as shown and described.

DESCRIPTION

FIG. 1 is a rear perspective view of an actuator button showing our design;

FIG. 2 is a front top perspective view thereof;

FIG. 3 is a rear top perspective view thereof;

FIG. 4 is a top view of thereof; and,

FIG. 5 is a rear view thereof.

The broken lines in the drawings represent portions of the actuator button that form no part of the claimed design.
